MAX SCHUPPE, OF BROOKLYN, NEW YORK, ASSIGNOR TO WALES ADDING MACHINE COMPANY, OF WILKES-BARRE, PENNSYLVANIA, A CORPORATION OF PENNSYLVANIA.

CALCULATING-MACHINE.

1,323,381.

Specification of Letters Patent. Patented Dec. 2, 1919.

Application filed April 21, 1919. Serial No. 291,512.

To all whom it may concern:

Be it known that I, MAX SCHUPPE, a citizen of the United States of America, residing in the borough of Brooklyn, Kings county, city and State of New York, have invented new and useful Improvements in Calculating-Machines, of which the following is a specification.

In particular, the present invention relates to novel means to enable calculating machines to compute fractions as distinguished from cardinal numbers of the decimal system, and is adapted for any such fractional divisions, as, for instance, the duodecimal, in which feet and inches, pounds and bushels, pounds and ounces (troy weight), hours and minutes (5 minute intervals) and British pounds and shillings, are computable, or the sextodecimal system in which 20 drams, ounces and pounds (avoirdupois weight), are computed.

As calculating machines generally, and especially in this country, have been devised to compute according to the decimal system, a fixed construction has developed due to a desire to arrange the parts as compactly as possible consistent with good practice, which, while readily lending itself to change where ordinal fractions of greater value than tenths are to be calculated, is not as elastic where ordinal fractions of lesser value than tenths are to be accumulated.

This is due in part to the limited number of teeth which may be formed on a pinion of a certain diameter, in a commercially practical machine, and also to the limited clearance or room afforded the various mechanisms operating to effect the accumulation of amounts on counters controlled by such pinions.

Consequently, the introduction into machines designed and constructed for operation according to the decimal system, of counters arranged to compute according to the duodecimal system, has heretofore necessitated the extension of the paths of travel of the driving members for such counters over and beyond the paths of travel of the similar driving members associated with the decimal counters, and such expansion has practically taken up the available clearance provided in such machines.

This condition will be better understood

by a concrete illustration. The counters of machines arranged for the decimal system 55 may be peripherally inscribed with a single set of numerals from "1" to "0" in ascending order, or with two sets of numerals arranged in tandem, or succession from "1" to "0" in ascending order. 60

In the first instance, the counters are respectively provided with pinions of ten teeth, and a complete revolution is necessary to add amounts to the capacity of the wheels, before the excess "1" is transferred to the 65 counter of next higher denomination.

In the second instance, the counters are respectively provided with pinions having twenty teeth, and need only make a half revolution to complete the capacity of one 70 denomination and transfer the extra "1" to the counter of next higher denomination.

As the drive members which turn the counters, reciprocate back and forth relatively thereto, it is evident that the length 75 of stroke of such drive members, in a machine constructed to add according to the decimal system, must be at least equal to nine times the circular pitch of the pinion, in order to turn the counter from its "0" 80 position to its "9" position, the carrying mechanism, in denominations above the units denomination, operating to turn the counter pinion through the remaining step or increment of movement to complete a full 85 revolution of a ten-tooth pinion, or a half revolution of a twenty-tooth pinion.

It is customary, therefore, in constructing calculating machines, to provide room for the necessary stroke of the drive members, 90 plus a clearance to insure their proper operation, and in view of such fixed limits, it is only possible, in many instances, to permit the drive members to have but a slightly longer stroke, say, enough to enable the 95 drive members to turn the counter pinions through an angle equal to two additional steps or increments of movement, the corresponding pinions being changed to have twelve or twenty-four teeth, as the case may 100 be, to calculate twelfths, in accordance with the duodecimal system.

The extension of the stroke of the drive member from a distance equal to nine times the circular pitch of the pinion to a distance 105 equal to eleven times the circular pitch of

the pinion, takes up the available clearance usually provided for the drive members in a calculating machine arranged to accumulate tenths, and hence, when it is desired to still further reduce the ordinal value of the fractions to be accumulated, a further increase in the length of stroke of the drive member would be necessary, under the above principle of operation, which extended stroke cannot be accommodated in the space usually provided for the operation of the decimal-accumulating drive members.

It might be thought that a pinion of the size of the ten-toothed pinion, for instance, might be provided with a greater number of teeth, say 16, so that the drive member, in its same length of travel or stroke, would turn the pinion through a distance equal to fifteen times its circular pitch, but this is impractical because the size and number of the teeth determines the size of the pinion, and the sixteen teeth formed on the circumference of a pinion adapted for ten teeth, would be too small and fine for commercial use in an adding machine, wherein the pinions and drive members are relatively engageable and disengageable, and extreme accuracy of operation is required to determine the stroke of the drive member; the angle through which the counter is turned thereby, and, in listing machines, the correct positioning of the proper types at the printing line.

One object of the present invention is to increase the range of computation of which machines designed and built for operation according to the decimal system, shall be capable of extension, by enabling the installation in such machines, of means to accumulate fractions, the units of which are of lesser value than tenths, without changing the construction other than in the particular denominational trains of mechanism directly affected.

In carrying out this object, I have contrived to compound the leverages in such manner that the throw or travel thereof in the space usually provided for the operation of the regular drive members, results in imparting a greater number of increments of movement or steps to the counter, than the regular drive members are capable of imparting to their counters, which enables the use of pinions and drive members having the same sized teeth as in the decimal accumulating denominations.

To this and other ends, my invention includes certain novel features and combinations of parts, all of which will be more fully set forth hereinafter and particularly pointed out in the claims.

In the accompanying drawings, Figure 1 is a longitudinal cross-sectional view through a Wales calculating machine, on line B—B of Fig. 3, showing the usual mech-

anism for accumulating and listing in accordance with the decimal system;

Fig. 2 is a similar view, on line A—A of Fig. 3, showing one embodiment of my invention, as applied to a decimal calculating machine, for accumulating sixteenth fractions;

Fig. 3 is a fragmentary top plan view, illustrating the combination of the sixteenth fraction accumulating mechanism, with the decimal accumulating mechanism;

Fig. 4 is a detail side view of the denominational counter for sixteenth fractions;

Fig. 5 is a detail edge view of the same, showing the separate carry-tripping and total alining members; and

Fig. 6 is a diagrammatic view of the drive mechanism for the fractional counter.

The well known Wales calculating machine is shown in U. S. Patents to Wales 797,032, August 15, 1905; McFarland and Wales 880,157, February 25, 1908; Bickford 1,069,104, August 5, 1913, and 1,132,516, October 6, 1914; Wilgus 1,133,596, March 30, 1915, and Pentecost 1,238,809, September 4, 1917, to which reference is made for a more complete understanding of the mechanism in connection with which I have chosen to illustrate one embodiment of my invention, although the idea is not confined in its application to the Wales machine.

Such machine is, in effect, composed of a variable number of denominational trains of mechanism, each of which trains includes a denominational row of numeral keys 117, (Figs. 1 and 3), a denominational row of stops 115, the individual members of which are separately controlled by the individual keys of the same denomination, a denominational counter 490 on which the digits represented by the keys, are accumulated, a denominational rack or drive member 310 for the counter, the rack and counter being relatively engageable and disengageable, a denominational typecarrier 514 operable synchronously with the drive member 310 and equipped with a row of types 561 corresponding to the inscriptions on the denominational row of keys 117, and a denominational printing hammer 510.

Means to advance and retire the drive racks, and to control the printing hammers, are also provided.

The numeral-bearing keys 117 of each denominational train are arranged in rows from "1" to "9" (see Fig. 3) extending from front to rear of the keyboard, to compute in accordance with the decimal system. Each key 117 is connected by a lever 116 to an individual stop 115 (Figs. 1 and 3), the stops being arranged in files corresponding with, and generally directly behind the rows of numeral keys 117, the upper ends of the stops projecting upwardly through aper-

tures formed therefor in a suitable housing 113.

Depression of any of the numeral keys 117 against the tension of its spring 180, rocks its lever 116 pivoted at 151, to project its corresponding stop 115 above the upper ends of the remaining stops in the same denominational file, and into the path of its denominational rack or drive member 310 supported near its forward end, at 361^c on a front arm 312 journaled on a cross shaft 300, and at its rear end, at 350, to the upper end of a rear arm 311 journaled on a cross rod 301.

15 A latch 114 common to each file of stops 115, and pivoted at 114^m, locks the projected stop in effective position against the tension of the restoring spring 180.

20 A restraining and restoring bar 205 supported in fingers 265^m depending from a rocking bar 265, lies in front of the entire series of front arms 312 supporting the denominational drive members 310, to normally retain the drive members in their 25 retired positions against the tensions of individual drive springs 383 connected to the rear supporting arms 311 and to the restraining and restoring bar 205, respectively.

In such position, the front ends of the 30 drive members 310 lie in rear of the rear-most stops 115 of the respective denominational files of stops, the stops in each file being arranged at graduated intervals along the line of advance of their corresponding 35 drive members 310, to arrest the latter at various points in their advance.

30 In an adding operation, after the numeral keys 117 representing the amount to be accumulated, have been depressed, the 40 main drive shaft 200 (Fig. 1) is turned on its forward stroke, against the tension of the restoring spring 285 connected to a crank 228 on the main shaft, to withdraw the restraining and restoring bar 205 (through 45 mechanism not herein shown, but fully disclosed in the above mentioned patents).

The restraining and restoring bar 205 on its withdrawal, further tensions the drive springs 383 to advance the drive members 310 until the latter are arrested by the projected stops 115, or by denominational detents 221 journaled on a cross shaft 202 and overlying the respective files of stops.

50 The stops 115, when projected to effective position, displace the corresponding detents 221, the remaining detents operating to arrest the drive members corresponding with those denominations wherein no keys 117 have been depressed.

55 In an adding operation, the drive members 310 advance relatively to their denominational counters or numeral wheels 490, the latter being journaled for independent rotation on a counter axle 400.

Individual pinions 435 turning with each 65 counter, are adapted to mesh and unmesh with their corresponding racks or drive members 310. Normally the counters 490 remain disengaged from their drive members 310, as shown in Fig. 1. The engagement and disengagement of the counter pinions 435 and their drive members is effected through mechanism (not herein shown, but disclosed in Wilgus 1,133,596) operated by the main drive shaft 200. 75

Thus, in an adding operation, as the main drive shaft approaches the end of its forward stroke, and after the drive members 310 have completed their advance, it trips counter-disengaging and supporting mechanism (not shown) to enable the counters to engage their drive members, such engagement continuing throughout the return stroke of the main drive shaft, during which the restraining and restoring bar 205 presses 80 against the forward arms 312 to retire the drive members 310, until, near the end of the return stroke, and after the drive members are retired, the main drive shaft actuates the counter-disengaging and supporting 85 means (not shown) to lift the counters out of mesh with their drive members 310. 90

The drive members 310 during their retirement, turn the counters 490 to register thereon the amount set up on the keys. 95

The main drive shaft 200, near the end of its return stroke, operates the usual rock shaft 201 (Fig. 1) to swing tappets 252 carried thereby, against ears 114^p of the latches 100 114 to release the latter and free the projected stops 115 and depressed keys 117 to the action of their restoring springs 180.

The counter pinions 435, in the present instance, are each equipped with twenty teeth, and the counters are each inscribed with two 105 sets of digits from "1" through "9" to, and including "0", in ascending order, arranged in tandem or succession at stepped intervals about the periphery thereof, so that if a counter stands with one of its zeros, at the 110 reading line, a half revolution will turn the counter until the zero of the second set of digits appears at the reading line.

In effecting decimal accumulations, it is never necessary to add a digit greater than 115 9, and hence, the travel of the rack or drive member 310 need never, and in practice, does not exceed the distance necessary to turn the counter from "0" to "9", or a distance equal to nine times the circular pitch 120 of the pinion 435, plus a sufficient clearance to accommodate play of the parts, and to lift the cipher types to the printing line, as is well understood in the art.

Also the housing 113 is of a width to conveniently accommodate a file of but nine stops 115. 125

Oppositely extending trip arms 411 (Fig.

1) suitably located on the counters 490, operate triggers 612 against the tensions of their springs 681, to release the customary carrying members (not shown) for operation, as the counters pass from "9" to "0" at the reading line, whereby to transfer the excess "1" to the counter of next higher denomination, all as more clearly explained in the patent to McFarland and Wales 880,157, 10 heretofore referred to. In the usual form, the laterally turned lip 612^m of each of the triggers lies in the path of rotation of its trip arms 411, there being a trip arm for each series of digits on the counter, the 15 opposite ends of which trip arm lie in a common plane.

The carrying trip arms 411 also operate in the usual Wales construction to arrest the counters 490 with the zeros at the reading line, by contact with the total alinement bar 412 journaled on a cross rod 403 and normally in idle position.

When it is desired to clear the machine, the total alinement bar 412 is rocked into 25 the paths of travel of the trip arms 411 to arrest the latter when the counters are in their zero positions, all as set forth in U. S. patent to Bickford 1,069,104 above mentioned.

30 To effect the imprint of amounts set up on the keyboard, each supporting arm 311 (Fig. 1) rocks a rearward extension 311^m thereof, a link 515 connecting each individual extension 311^m with its corresponding 35 denominational type bar or carrier 514, the head of which carries a row of types 561, the members of which correspond to the inscriptions on the associated row of keys controlling the respective typecarriers.

40 It is obvious that there must be such relation of the intervals between the stops 115, the intervals between the numerals on the counters 490, and the intervals between the types 561, that a harmonic motion results, 45 whereby the rack or drive member 310, on its advance, and after its arrest by the stop controlled by the "3" key, for example, will have lifted the typecarrier 514 to position the "3" type at the printing line, and will 50 also, on its retirement, turn the counter through an arc equal to three times its circular pitch, to accumulate the "3" thereon.

Each extension 311^m contacts a lip 513^m on a denominational trip bar 513 to hold 55 the latter in lowered position against the tension of its spring 583. As the extension 311^m rises, the spring 583 causes the trip bar to follow until the upper end of the trip bar strikes the tail of an individual hammer latch 511 pivoted on a cross rod 504, and releases the latch from the notch of its 60 denominational printing hammer 510 driven by a spring 580, but normally restrained by a universal catch 518 fast on a cross shaft

502. The individual latches 511 are provided with the usual cross-overs 511^m to trip the adjacent latch or latches to the right in case no key 117 is depressed in the corresponding denominations.

As the main drive shaft nears the end of 70 its forward stroke, it operates mechanism (not herein shown, but found in Pentecost 1,238,809), to disable the universal catch 518 and thereby free the hammers to the action of their springs 580, which drive the hammers against plungers 562^b, to force the latter against the types 561 positioned at the printing line, and thereby effect an impression of the types.

The hammers are recocked by the main 80 drive shaft during its return stroke, and the drive members 310, during their retirement, lower the extensions 311^m and type carriers 514 to their positions of rest. The extensions 311^m, in turn, force the trip bars 513 downwardly against the tension of the springs 583, to release the individual latches 511 to the action of their restoring springs 581, which snap the latches to effective position relatively to the recocked hammers 510.

85 The foregoing is the usual Wales construction and constitutes a part of the present invention only in so far as it combines with the novel features hereinafter set forth.

90 Adaptation of the foregoing decimal calculating mechanism to the accumulation of fractions, as quarters, eighths or other fractional divisions of greater value than tenths, has heretofore been readily accomplished by inscribing the periphery of a counter with two sets of fraction designations, as eighths, for instance, arranged in tandem, in ascending order, with ciphers or blank spaces intervening between the two 95 sets, the fractional designations being equally spaced about the periphery. Such counter generally occupies the lowest denominational position on the keyboard, and is equipped with a pinion of the same 100 diameter as the regular pinions 435, but having 16 equidistant teeth instead of 20, and adapted to mesh with a rack similar to the regular drive members 310 except that it carries 9 teeth somewhat larger than the usual 11 teeth on a decimal drive member. Oppositely extending carry-tripping arms on the fractional counter, and similar 105 to the regular tripping arms 411, operate the transfer mechanism to effect the registration of the excess "1" on the counter of next higher denomination when the capacity of the fractional counter is exceeded. The carrying mechanism will thus be tripped at each half-revolution of the counter.

110 The only differences existing between the regular counters and the above fractional counter are that the circular pitch of the

teeth of the fractional counter is slightly greater than the circular pitch of the regular counters, and the fractional designations are inscribed at correspondingly greater intervals about the periphery of the fractional counter.

In addition, the seven stops for arresting the fractional rack or drive member are spaced relatively farther apart across the 10 housing 113 than are the nine regular stops 115, to enable the fractional rack to turn its counter through a greater angle of rotation to compensate for the greater intervals between the fractional designations, but it is 15 important to remember that it is not necessary to increase the stroke of the fractional drive member beyond the length of stroke of the regular drive members of the decimal accumulating machine.

20 To adapt a decimal calculating machine to the accumulation of fractions of lesser value than tenths, however, presents an entirely different problem, in view of the limited space within which the supporting 25 arms 312, 311 may swing, and the consequent limit to the stroke of the drive members 310, coupled with the restricted width of the housing 113, which is proportioned for nine stops, and while it is possible, by utilizing 30 the clearances, to equip decimal calculating machines with means to accumulate according to the duodecimal system, the same principle is not capable of extension to enable these machines to accumulate sixteenth 35 fractions, owing to the fact that at times it is necessary to turn the counter through fifteen-sixteenths of a complete circle, by the stroke of the driving rack in a substantially rectilinear line, and the limits are not sufficiently comprehensive to permit such scope 40 of travel of the driving rack.

Therefore, I have changed the construction of the counter drive mechanism to enable the latter to operate in the restricted 45 space provided for decimal drive members, and yet impart the required angle of rotation to the counter without necessitating any change in the proportions of the frame and major elements of the decimal calculating 50 machine to which it is applied.

In fact, my invention is merely substituted in place of the units or other selected train of denominational mechanism of the decimal calculating machine.

55 Pursuant thereto, I replace the units bank of keys 117 of the decimal calculating machine, with two rows of fraction-designated keys 117^x, 117^y (Fig. 3) the eight odd-numbered fractional keys from "1" to "15", in 60 one row, and the seven even-numbered keys from "2" to "14" in the remaining row.

Levers, not shown, but similar to levers 116 connect the keys 117^x individually with their respective stops 115^x, the free ends of

which project upwardly in file through the 65 housing 113.

Similarly, levers 116^y (Fig. 2) pivoted at 151^y connect the keys 117^y with the corresponding stops 115^y arranged in a file alongside the file stops 115^x, (Fig. 3) the files of 70 stops 115^x and 115^y, being relatively staggered, and the intervals between the stops of either file 115^x or 115^y being greater than the intervals between the regular decimal stops 115, since, in the particular form of my invention selected for illustration, there are but 7 stops in one file and 8 in the other, but the intervals between the alternate stops in the two files, are less than those between the stops 115 of the regular denominational files. 80

Detents 221^x overlie the respective files of stops 115^x and 115^y, a bound 1 connecting the detents, whereby the displacement of either detent will carry the remaining detent with it. 85

The stops 115^x and 115^y arrest the excursions of a single bifurcated positioning bar or member, one branch 310^x of which, coacts with the file stops 115^x, the remaining branch 310^y adapted to coact with the 90 file of stops 115^y. The branches of the bifurcated positioning member are respectively pivoted intermediate their ends, at 361^x to the upper ends of front supporting arms 312 similar to the regular front supporting arms 312, the rear end of the forked or bifurcated positioning member being pivotally connected at 2 to the forwardly projecting arm of a bell crank lever 3 journaled on the familiar cross shaft 607. 100 This lever is cut away or recessed, as at 4, (Fig. 2) to clear the usual shaft 600 on which are journaled the carrying rockers of the well known Wales calculating machine, reference being directed to the pending application of A. Pentecost, Serial No. 23,306, filed April 23, 1915 for a more complete 105 understanding of this mechanism.

A spring 385^m (Figs. 2 and 3) connected at one end to an ear 5 on the bell crank lever 3, and at its opposite end to the restraining and restoring bar 205, operates to advance the lever 3 and positioning member 310^x, 310^y, until the latter is arrested by the detents 221^x or by any of the stops 115^x, 115^y.

In this connection, I would direct attention to the fact that the arrest of either branch 310^x, 310^y of the positioning member, arrests the bell crank lever 3 and its 120 connected parts.

A link 6, one end of which is pivotally secured to the ear 5 of the bell crank lever 3, connects the lever with a toothed segment 7 at a point 8, the segment being journaled on the cross shaft 600, directly beneath a counter 490^m bearing a single series of numerals from "1" through "15" to "0" 125

spaced equidistantly about its periphery to indicate sixteenth fractions. The counter 490^m is journaled on the counter axle 400 in line with the regular counters and carries a pinion 435^x of substantially the same diameter as the regular twenty-tooth pinions 435, but having sixteen teeth to mesh with the segment 7. The axle 400 and the cross shaft 600 are preferably in the same vertical plane.

To briefly recapitulate, it being inconvenient to arrange a single file of fifteen stops across the housing 113, and it also being inconvenient to arrange to permit a regular drive rack or positioning member 310 to have a reciprocatory travel sufficient to enable it to turn a counter fifteen steps or increments of movement at one stroke, without materially changing the entire machine, I have devised the above explained embodiment to effect the same result.

By arranging the fifteen stops 115^x, 115^y in two files, and staggering the individual stops of one file relatively to those in the remaining file, a slight increment of advance is permitted the dual positioning bar 310^x, 310^y between successively alternate stops in the respective files.

In other words, and as shown in Fig. 3, the rearmost stop of the file of stops 115^y is slightly in advance of the rearmost stop in the file of stops 115^x, and so on.

Obviously, however, the distance through which the dual positioning bar advances from the rearmost stop of the file 115^x to the rearmost stop of the file 115^y is considerably less than the distance between the regular stops 115.

On the other hand, the numerals on the fraction - representing counter 490^m are spaced farther apart than are the numerals on the regular counters 490 and the same is true of the circular pitch of the sixteen teeth of the fractional pinion 435^m as compared with the twenty teeth of the regular pinions 435.

The problem is, then, to enable the dual positioning member (whose respective increments of movement, broadly speaking, are each of less length than the respective increments of movement of the regular rack bars 310) to advance the segment or drive member 7 through a greater angular distance than that through which the regular rack bars advance.

This means, in effect, that while the same number of teeth on the segment 7 are employed to turn the fraction pinion 435^m through two increments of movement, for instance, that are required by the regular rack bars 310 to turn the regular pinions 435 through two increments of movement, yet, because of the greater circular pitch of the fractional counter, its pinion and seg-

ment, than the circular pitch of the regular counter, its pinion and drive rack, the former actually transverses a greater angular distance than the latter.

In solving this problem, I have devised a compound leverage, whereby the slight increments of movement permitted the positioning member 310^x, 310^y, by the digital stops 115^x, 115^y, are amplified to advance the segment 7 to its proper position relatively to its counter and pinion.

As is well known, the amount of throw or movement imparted by a rotating crank to a driven part is at the minimum as the crank approaches and leaves its two dead center positions, and is greatest as the crank passes a point half way between its dead center positions.

I utilize this principle in the present instance, the segment 7 corresponding to the driven member and the lever 3 to the crank. Thus it will be seen that the radius 607, 5, (Fig. 6) lies at a considerable angle to the dead center radius 607, 600, when the parts are in their home positions, shown in Figs. 2 and 6, and further, that the radius 600, 8 lies at substantially right angles to a line drawn between the fulcrum 600 of the toothed segment and the point 5 at which the transmitting link 6 is connected to the drive lever 3, so that immediately the lever 3 commences its advance, it will rock the toothed segment 7 through the link 6, on its arc of travel of greatest activity.

If the lever 3 was directly connected to the segment 7, the travel of the latter, especially when advancing to the higher values of sixteenth fractions, would slow up, because the radius 607, 5, would constantly approach nearer the dead center line 607, 600, to avoid which I interpose the link 6, connected to the lever at 5 and to the segment at 8. By means of this connection, I compound the leverages 607, 5, and 600, 8, in such manner that as the radius 607, 5 approaches the dead center line, the radius 600, 8 shifts farther away from its dead center line, to compensate for any slowing up of the radius 607, 5 and effect a constant advance of the segment 7.

The fraction counter 490^m with its pinion 435^x moving with the regular counters 490 and their pinions, drops into mesh with the segment 7 at the end of the forward stroke of the main shaft 200, and the restraining and restoring bar 205 by its contact with the front arm 312, retires the lever 3, link 6 and segment 7 in the same manner that it retires the regular rack bars 310.

Because the fractional counter 490^m is arranged to make a complete revolution before a transfer is effected onto the counter of next higher denomination (the units counter in this instance) a slight change is necessary in

the carry tripping and zero-resetting mechanism mounted on the fractional counter.

It will be remembered that the regular trip arms 411 extend diametrically across the respective denominational counters 490, the opposite ends of each arm 411 lying in the same vertical plane.

As seen in Figs. 3, 4 and 5, the fractional counter 490^m carries a radially extending carry tripping member 411^x to contact the lip 612^x of the spring-pressed trigger 612 of the carrying mechanism, the radial member not extending diametrically across the counter. And since the location of the radial tripping member is such relatively to the peripheral arrangement of numerals on the counter, as to trip the carrying trigger 612 at the time when the counter is passing from "15" to "0" at the line of sight, it will 10 not arrest the counter with its "0" at the sight opening during a clearing operation, for which reason, the counter 490^m carries a second radially-extending zero-aligning member 411^y arranged 15 in a plane parallel with the trigger-tripping member 411^x so as to avoid contact with the trigger lip 612^m. The outer end of the zero-aligning member 411^y is turned laterally away from the trigger-tripping member, as 20 shown in Figs. 3 and 5, to contact the total alignment bar 412 which, it will be noted, is recessed at 412^x in line with the trigger-tripping finger 411^x to allow the latter to pass when taking a total or clearing the machine.

In order to print the fractions set up on the two right hand banks of keys 117^x, 117^y, I provide the lever 3 with a rearwardly and downwardly inclined extension 9 (Fig. 2). 40 A short link 515^x connects the extension at 10, with the lower end of a typecarrier, 514^x, whose head is equipped with a vertical row of types 561^x from "1" to "15."

A regular impression mechanism, including a hammer 510, driven by a spring 580, and restrained by an individual latch 511, and the universal pawl 518, strikes a firing pin or plunger 562^x to drive the latter against any of the types 561^x which may be positioned at the printing line on the platen 2094..

A spring-actuated bar 513^x controlled by the extension 9, releases the individual latch 511 in the same manner as in the regular denominations and heretofore explained.

Preferably, the uppermost type member which in the other denominations prints a cipher, is replaced in the fractional denomination by a dummy 563^x, which makes no impression on the paper when no fractional key has been depressed, or in totaling, when the fractional counter 490^m is at zero.

Obviously, the positioning of the types 561^x at the printing line is controlled by the

throw of the long radius 607, 10 regulated by the stops 115^x, 115^y, whereby each slight increment of advance permitted the dual positioning bar 310^x, 310^y, by the successively alternate stops 113^x, 115^y is increased to lift the typecarrier 514^x a distance equal to that 70 between the centers of the respectively successive types 561^x.

It is obvious that my invention is not confined to the calculation of sixteenth fractions only, but may be adapted for the accumulation of any fractional divisions, and may be used in machines equipped to calculate monetary values of foreign countries based on other than the decimal system, by alterations in the length of the radius 600, 8, or 607, 5, 80 and it is just as applicable to the calculations of fractions of greater unitary value than tenths, as to those of lesser value.

Changes may be made in the form and arrangement of the several parts set forth, 85 without departing from the spirit and scope of my invention.

What I claim as new, is—

1. In a calculating machine, the combination with regular accumulating mechanism, including counter pinions; and driving racks therefor, having a limited stroke, and with which the pinions engage and disengage; of a special counter pinion having its teeth arranged at a greater circular pitch 95 than the teeth of the regular counter pinions; an actuating member therefor, having a longer path of travel than the driving racks; a positioning member having a stroke substantially equal to the stroke of the driving racks; and a compound leverage to connect the positioning member and the actuating member for the special counter pinion, whereby the limited stroke of the positioning member is augmented when transmitted 10 to the actuating member.

2. In a calculating machine, the combination with a regular accumulating mechanism, including counter pinions; and driving racks with which the pinions engage and disengage; of a special counter pinion associated in series with the regular counter pinions; a plurality of rows of keys to control the angular rotation of special counter; a plurality of files of stops corresponding 11 with the rows of keys, the stops in one file arranged in staggered relation to the stops in the adjacent file; a single positioning member having branches to coact with the respective files of stops; a swinging means 12 to support the forward end of the positioning member; a fulcrumed driving lever connected to the positioning member to shift the latter; an actuating member for the special counter; and a link connection between the driving lever and actuating member.

3. In a calculating machine, the combination with a regular accumulating mech-

- anism, including counter pinions; and driving racks with which the pinions engage and disengage; of a special counter pinion associated in series with the regular counter pinions; a plurality of rows of keys to control the angular rotation of the special counter; a plurality of files of stops corresponding with the rows of keys, the stops in one file arranged in staggered relation to the stops in the adjacent file; a single positioning member having branches to coact with the respective files of stops; means to support the forward end of the positioning member; a fulcrumed driving lever connected to the positioning member to shift the latter; an actuating member for the special counter; and a link connection between the driving lever and actuating member, the radius between the fulcrum of the driving lever and the point at which the link is connected to the lever, being longer than the radius between the fulcrum of the lever and the point at which the positioning member is connected to the lever.
4. In a calculating machine, the combination with a regular accumulating mechanism, including counter pinions; and driving racks with which the pinions engage and disengage; of a special counter pinion associated in series with the regular counter pinions; a plurality of rows of keys to control the angular rotation of the special counter; a plurality of files of stops corresponding with the rows of keys, the stops in one file arranged in staggered relation to the stops in the adjacent file; a single positioning member having branches to coact with the respective files of stops; means to support the forward end of the positioning member; a fulcrumed driving lever connected to the positioning member to shift the latter; an actuating member for the special counter; and a link connection between the driving lever and actuating member, the radius between the fulcrum of the driving lever and the point at which the link is connected to the lever, being longer than the radius between the fulcrum of the lever and the point at which the positioning member is connected to the lever, and the point of connection of the link to the actuating member bearing a definite relation to the axis of rotation of the actuating member, and to the radius between the fulcrum of the lever and the point at which the link is connected to the lever.
5. In a calculating machine, the combination with a regular accumulating mechanism, including a series of denominational counter pinions; and driving members therefor, the pinions and driving members adapted for engagement and disengagement; and denominational files of key-set stops to control the excursions of the driving members; of a special counter pinion associated in se-
- ries with the regular counter pinions, and having teeth differing in circular pitch from the teeth of the regular counter pinions; an actuating member therefor having teeth of a corresponding pitch and adapted to have a longer travel than the drive members for the regular pinions; a plurality of files of key-set stops; a single positioning member having branches to coact with the respective files of stops; a fulcrumed drive lever connected to the positioning member; and a link to connect the actuating member with the drive lever at a point further removed from its fulcrum than the point of connection of the positioning member and lever.
6. In a calculating machine, the combination with a regular accumulating mechanism, including a series of denominational counter pinions; and driving members therefor, the pinions and driving members adapted for engagement and disengagement; and denominational files of key-set stops to control the excursions of the driving members; of a special counter pinion associated in series with the regular counter pinions, and having teeth differing in circular pitch from the teeth of the regular counter pinions; an actuating member therefor having teeth of a corresponding pitch and adapted to have a longer travel than the drive members for the regular pinions; a plurality of files of key-set stops; a single positioning member having branches to coact with the respective files of stops, the positioning member having a maximum excursion substantially equal to the maximum excursion of the regular driving members; a fulcrumed drive lever connected to the positioning member; and a link to connect the actuating member with the drive lever at a point farther removed from its fulcrum than the point of connection of the positioning member and lever.
7. In a calculating machine, the combination with a regular accumulating mechanism, including a series of denominational counter pinions; and driving members therefor, the pinions and driving members adapted for engagement and disengagement; and denominational files of key-set stops to control the excursions of the driving members; of a special counter pinion associated in series with the regular counter pinions, and having teeth differing in circular pitch from the teeth of the regular counter pinions; an actuating member therefor having teeth of a corresponding pitch and adapted to have a longer travel than the drive members for the regular pinions; a plurality of files of key-set stops, the stops in one file arranged in staggered relation to the stops in the adjacent file, the intervals between the stops in alternate files being less than the intervals between the stops in the regular denominational files; a single position-

- ing member having branches to coact with the respective files of stops; a fulcrumed drive lever connected to the positioning member; and a link to connect the actuating member with the drive lever at a point farther removed from its fulcrum than the point of connection of the positioning member and lever.
8. In a calculating machine, the combination with regular denominational trains of accumulating mechanisms, each including a file of key-set stops; a drive member whose excursions are controlled thereby, and a counter pinion, the drive member and counter pinion adapted for engagement and disengagement; of a special train of accumulating mechanism, including a special counter pinion, the teeth of which differ in circular pitch from the regular counter pinions; a suitably journaled toothed segment to turn the special counter pinion; a plurality of rows of keys; files of stops corresponding with the respective rows of keys, the stops in one file arranged in staggered relation to the stops in the adjacent file; a positioning member, having branches to coact with the respective files of staggered stops; means to pivotally support the forward end of the positioning member; a suitably fulcrumed drive lever to which the positioning member is pivotally connected; means to advance and retire the lever; and a link to connect the toothed segment and the drive lever.
- 35 9. In a calculating machine, the combination with a counter pinion; and an actuating member therefor; of a plurality of key-set stops to variably arrest the actuating member, the stops arranged in files side by side; a positioning member, having a branch appropriated to each file of stops; means to pivotally support the forward end of the positioning member; a suitably fulcrumed drive lever to which the positioning member is pivotally connected; means to advance and retire the drive lever; and means to connect the actuating member with the drive lever at a point more remote from the fulcrum of the lever than the point at which the positioning member is connected to the drive lever.
10. In a calculating machine, the combination with a counter pinion; of an actuating member therefor; a suitably-fulcrumed drive lever; means to connect the actuating member and drive lever; a branched positioning member pivotally connected to the drive lever; a plurality of files of key-set stops, to correspond with the several branches of the positioning member; and connected detents to arrest the positioning bar when the stops are idle, and simultaneously displaceable by a stop in any of the files.
11. In a calculating machine, the combination with a denominational counter; and
- an actuating member therefor, the counter and actuating member being relatively engageable and disengageable; of a plurality of keys; a plurality of stops controlled by the keys and arranged in parallel files; a 70 positioning member having a separate branch associated with each file of stops; front arms mounted to rock forwardly and rearwardly, and pivotally connected to the respective branches of the positioning member; an independently journaled rocking lever to pivotally support the rear end of the positioning member; means to rock the lever; and means to connect the actuating member with the lever.
12. In a calculating machine, the combination with a counter axle; a counter pinion rotatable thereon; a cross rod located in the same vertical plane with the axle; and an actuating member journaled thereon and 75 having an arcuate travel, to coact with the counter pinion; of a series of files of settable stops; a positioning member having a branch appropriated to each file of stops; rocking supports for the positioning member; a suitably fulcrumed drive lever pivotally connected to the positioning member; means to advance and retire the drive lever; and means to connect the actuating member and the drive lever, said means attached to 80 the drive lever at a point more remote from its fulcrum than is the positioning member; the connecting means being attached to the actuating member at a point substantially at right angles to a line between the fulcrum of the actuating member and the point of attachment of the connection and the drive lever, to enable the drive lever to rock the actuating member through its arc of greatest activity relatively to the counter.
13. In a calculating machine, the combination with an axle, a series of denominational pinions journaled on the axle, and having teeth arranged at a predetermined circular pitch; denominational reciprocating drive members for the respective pinions having teeth of a corresponding circular pitch, and with which the pinions are adapted to mesh and unmesh; denominational carrying triggers; means driven by the respective pinions to trip the corresponding triggers a plurality of times for each complete rotation of any of the pinions; and a total refinement bar shiftable into the path of the trigger-tripping means to arrest the pinions 100 in their zero positions; of a fractional pinion journaled on the axle and having teeth of a greater circular pitch than the teeth of the denominational pinions; a segment having teeth of a corresponding circular pitch, 105 to drive the fractional pinion; a carrying trigger associated with the fractional pinion; means driven by the fractional pinion to trip the trigger once for each complete rotation of the last-named pinion; and a see- 110

ond member offset from its associated trigger-tripping means, and from the carrying trigger, and driven by the pinion to contact the total alinement bar to arrest the latter in its zero position, the total alinement bar being recessed to permit the passage of the trigger-tripping means.

14. In a calculating machine, the combination with a rotatable counter pinion; an actuating member therefor having an ar-

cuately travel; a series of files of settable stops; a positioning member having a branch appropriated to each file of stops; a suitably fulcrumed angular drive lever to one arm of which the positioning member is pivotally connected; means to advance and to retire the drive lever; and means to connect the actuating member and another arm of the drive lever. 15

MAX SCHUPPÉ.
